UNITED STATES PATENT OFFICE.

FREDERIC D. CHASE, JR., OF EVERETT, MASSACHUSETTS, ASSIGNOR TO WALKER-LONGFELLOW COMPANY, OF BOSTON, MASSACHUSETTS, A CORPORATION OF MAINE.

FOLDING CARD.

1,045,257.

Specification of Letters Patent. Patented Nov. 26, 1912.

Application filed March 2, 1912. Serial No. 681,149.

To all whom it may concern:

Be it known that I, FREDERIC D. CHASE, Jr., citizen of the United States, residing at Everett, in the county of Middlesex and 5 State of Massachusetts, have invented new and useful Improvements in Folding Cards, of which the following is a specification.

My invention is a folding card, especially adapted for mailing purposes, with means 10 to lock the parts in their closed position, the locking means being preferably so devised, that in the act of unlocking, a printed or written message may be turned into view beneath the eye of the addressee or operator.

15 In the drawings: Figure 1 is a front view of my new card, in locked relation; Fig. 2 the same, unlocked, inner view; Fig. 3 is a view of the locking disk; Fig. 4 is a rear view of part of Fig. 1; and Fig. 5 is an edge 20 view of Fig. 1.

As shown in the drawings, my new card consists essentially of two parts A and B, hinged together at one edge *x*, so that the two parts may be folded together. The 25 front sheet A has an opening or "sight," *a*, and may if desired have additional sights, as *a'*. Interposed between the two parts A and B, and pivotally connected to the front sheet A, at *d'* by an eyelet or the like, is a 30 revoluble member D, having a tongue *d*, preferably integral therewith, the two sides of which are respectively parts of concentric circles about the pivot *d'*. In the other 35 member B, of the card, are two slits, forming between them a bar *b*, which lies across the path of the locking member *d* as the member D is rotated, so that, by slipping the point or the free end of the member *d* under bar *b* and rotating the part D, the two parts 40 A and B may be securely locked together.

It will be obvious that the side of the part D, which is opposed to the part A, will be visible through the apertures or sights *a*, *a'*,

in the part A, and the part D may bear printed or written matter to be exposed as D 45 is revolved. In the drawings I have shown one application, in which, when the card is locked, for mailing, the front shows no message, but as D is rotated to unlock the card, the message will be discovered (see Fig. 1). 50

In the preferred form, shown in the drawings, the locking member is formed as a disk and is secured to the card at such a position that its lower edge projects, so that the disk may be turned by taking hold of the lower, 55 projecting edge.

It will be obvious that the part D may be secured to the rear member and the bar *b*, secured to the front member, if desired.

I claim:

1. The folding card above described, comprising a front and a rear member, a locking member having display matter thereon, pivotally secured between the front and rear members and a bar upon the member to 65 which the locking member is not secured, to engage the locking member, said front member being apertured to disclose the display matter when the locking member is revolved, all combined and operating substantially as 70 described.

2. The locking device above described, comprising front and rear members; a locking member pivotally secured between the front and rear members and carrying a tongue the two edges of which are respectively parts of concentric circles about the pivot point and a bar upon the member to which the locking member is not secured, to 75 engage the locking member.

Signed by me at Boston, Mass., this first day of March, 1912.

FREDERIC D. CHASE, JR.
